Garrison Smith and Henry Brown, of Philadelphia, Penna.

Assignors to

J. G. Abbott and Leibelle, of the same place.

Letters Patent No. 1,965. Dated June 21st 1864.

Design for the Plates of a Cooking-stove.

The schedule referred to in these letters is not a part of the same.

Scall whos it may concern:

Be it known that we, Garrison Smith and Henry Brown, of Philadelphia, County of Philadelphia, State of Pennsylvania, have invented or produced a new and original design for the top and side plates of a cooking-stove turned the "table-top"; and we do hereby declare the accompanying drawing with the following explanation of the same to form a full, clear and exact description of the said design.

Fig. 1 of the drawing is a sectional view of the top plate, and one of the side plates of a stove.

Fig. 2 an end view of the two plates.

Fig. 3 a side view of one of the side plates.

Fig. 4 a plan view of the top plate.

A is the top plate, and B the side plate of the stove.

The top plate is of the form represented in Fig. 4, and is edged with a plain moulding as.

The side plate Fig. 3 has a hollow square projection D, which forms a doorway, there being the corrugated ornament on the sides of this projection as shown in Fig. 2.

The side plate is edged with a moulding, a section of which is clearly illustrated at a fig. 1.

We claim. The figures and forms represented in and by the accompanying drawing, the whole forming a design for the top and side plates of a cooking-stove.
